UNITED STATES PATENT OFFICE

CHARLES M. YOUNG, JR., OF PHILADELPHIA, PENNSYLVANIA, ASSIGNOR TO LINK-BELT COMPANY, OF CHICAGO, ILLINOIS, A CORPORATION OF ILLINOIS

LOADER AND SEALING MEANS THEREFOR

Application filed June 3, 1929. Serial No. 367,918.

My invention relates to an improvement in loaders and sealing means therefor and has for one object to provide a new and improved type of sealed automatic measuring loading chute and skip hoist combination which will be especially adaptable for use with fine free flowing material.

Among the objects of the invention are to provide a pivoted combined cut-off gate and chute wherein means are provided to pack the moving parts against penetration by the fine freely flowing material so as to prevent jamming, binding and undue wear of the parts. Another object of the invention is to provide in combination with such gate and chute means for yieldingly and automatically taking up wear to maintain the parts permanently in proper working position. Other objects will appear from time to time in the specification.

My invention is illustrated more or less diagrammatically in the accompanying drawings wherein:

Figure 1 is a side elevation with the gate and hopper in discharge position.

Figure 2 is a similar elevation showing the gate closed.

Figure 3 is a section along the lines 3—3 of Figure 1.

Figure 4 is a section along the lines 4—4 of Figure 1.

Figure 5 is a section along the line 5—5 of Figure 2.

Figure 6 is a section along the lines 6—6 of Figure 1.

Figures 7 and 8 are sections through a modified form of packing means.

Like parts are indicated by like characters in all the figures of the drawings and specifications.

A is a storage hopper. Discharging downwardly therefrom is a fixed chute A² which terminates at A³ just out of the path of the skip hoist bucket A⁴ which bucket by means of the bail A⁵ and cable A⁶ may be caused to travel along the upwardly inclined tracks A⁷, being supported and guided by rollers A⁸ in engagement therewith. It will be understood that the angle of inclination of the tracks A⁷ is optional and these may even be

vertical in some instances without changing in any way the operation which forms the subject matter of the present invention.

Mounted on the underside of the chute A² are a plurality of bearing blocks B which support a trunnion shaft B¹, which shaft extends at each end beyond the side walls B² of the chute A². Mounted on the opposed ends of the trunnion shaft B¹ are side plates B³, B⁴, these two plates lying as shown in Figure 3 just outside of the side plate B². These side plates are jointed by a curved segmental sheet forming an undercut gate B⁵ adapted to travel just beyond the end of the chute A². This gate terminates in a stop member B⁶ adapted to engage the reinforcing flange B⁷ at the end of the chute A² to limit the upward movement of the gate. It will be understood, of course, that the ends of the side walls A² are curved to conform to the travel of and not interfere with the movement of the gate B⁵. B⁸ is an extension radially from the gate B⁵ which together with the extensions B⁹ from the side plates B³, B⁴ forms a pivoted chute. These members B⁹ are joined by a plurality of separated generally parallel staggered cleats B¹⁰ which so to speak form louvers in the top of the pivoted chute and leave a certain amount of clearance space for material banked up in the chute, but which taking into consideration the angle of flow of the material prevent escape of material from the top of the chute.

C are counterbalance arms extending rearwardly from the side plate and adapted to support an adjustable and removable counterweight, C¹. C² is a cushion spring, there being one on each side of the pivoted chute extending generally radially into the path of rollers C³ carried by gate operating arms C⁴ on the skip A⁴. These springs project into the paths of the rollers as indicated in Figure 2 so that as the skip descends these spring arms are engaged and the gate is rotated from the closed position of Figure 2 to the open position of Figure 1, the rollers traveling inwardly along these spring arms as indicated and cushioning the gate and chute against too sudden operation. The under-

side of the pivoted chute is adapted to be engaged by the curved upwardly disposed shoe C⁵ on the skip A⁴ to cause the skip on this upward movement to rotate the chute and gate into the closed position of Figure 2.

5 When coarse material is being handled the interlocking of the parts above discussed is ordinarily sufficient to prevent any leakage between the fixed and movable chute gate and other parts. It frequently happens, however, 10 when fine material or material that flows very freely is being handled that as the material piles up in the chute and even as it travels along the chute it flows out into the 15 spaces between the fixed and moving parts, causes binding and interferes with smooth operation. I provide, therefore, packing means to prevent such action. This packing means or sealing means takes the form of an 20 arcuate wear or packing strip D, held in place by means of the flush head bolts D¹ and nuts D² on the curved ends of the side plates B². Engaging these packing strips D are 25 packing or sealing strips D³ mounted on the side plates B³ B⁴ concentric with the strips D and adapted to travel therealong when 30 the combined chute and gate rotates. These strips D³ are anchored at one end by means of holding bolts D⁴, are yieldingly pressed 35 against the strip D by means of springs D⁵ in sockets D⁶ and are provided with tension adjusting screws D⁷. In that part of the structure where the strips D³ are adjacent the gate B⁶ they are held in position between it and 40 a curved flange D⁸. This flange D⁸ extends around to the top of the pivoted chute and there is an additional flange D⁹ extending upwardly from the upper terminus of the gate to the top of the pivoted chute, so that the 45 packing or sealing strip D³ while generally constrained, is given a certain freedom of motion radially to prevent binding and to permit it to properly position itself with respect to the fixed strip D, and also the strip D⁹, and above the gate the strips D³ and D⁹ 50 protect the adjustable tension springs and the space between the floating packing strip D³ and the wall B⁴ and assist in preventing escape of the material into the space between the side plates B² and B³ or B⁴.

It will be evident that while I have shown in my drawings an operative device, still many changes might be made both in size, shape and arrangement of parts without departing materially from the spirit of my invention and I wish therefore that my drawings be regarded as in a sense diagrammatic.

Referring to Figures 7 and 8, it will be noted that instead of the spring held engaging segmental rings, I provide two flexible strips F held on a flange F¹ together with a single flexible strip F² traveling between them. Under some conditions this would be a thoroughly satisfactory means of packing the device though it would not be as strong

and would be more appropriate for use in connection with material lighter than the material ordinarily used.

I claim:

1. The combination with a fixed chute having side walls and a pivoted combined gate and chute associated therewith having side walls, of sealing means interposed between said side walls to prevent escape of material into the space between them, said sealing means including a flexibly supported arcuate member generally concentric with the axis of rotation of the pivoted chute. 70

2. The combination with a fixed chute having side walls and a pivoted combined gate and chute associated therewith having side walls, of sealing means interposed between said side walls to prevent escape of material into the space between them, said sealing means comprising engaging arcuate members, one of them yieldingly pressed against the other, both concentric with the axis of rotation of the chute. 80

3. The combination with a fixed chute having side walls and a pivoted combined gate and chute associated therewith having side walls, of sealing means interposed between said side walls to prevent escape of material into the space between them, said sealing means comprising engaging arcuate members, one of them yieldingly pressed against the other, both concentric with the axis of rotation of the chute, guide means for the yieldingly supported member, adapted also to prevent ingress of material into the space behind it. 90

4. The combination with a fixed wall member and a pivotally movable wall member parallel therewith, of sealing means interposed between them, comprising an arcuate yieldingly supported sealing strip on one, adapted to engage and slide upon the other. 105

5. The combination with a fixed wall member and a pivotally movable wall member parallel therewith, of sealing means interposed between them, comprising an arcuate, yieldingly supported sealing strip on one, adapted to engage and slide upon the other, a plurality of separate springs engaging such strip and means for adjusting the tension on said springs. 110

6. The combination with a fixed wall member and a pivotally movable wall member parallel therewith, of sealing means interposed between them, comprising an arcuate, yieldingly supported sealing strip on one, adapted to engage and slide upon the other, a plurality of separate springs engaging such strip and means for adjusting the tension on said springs, a socket in which the spring is mounted, the adjusting means comprising a screw threaded in the socket and engaging the spring. 120

7. The combination with a fixed wall member and a pivotally movable wall member 130

parallel therewith, of sealing means interposed between them comprising an arcuate, yieldingly supported sealing strip on one, adapted to engage and slide upon the other, 5 curved flanges enclosing said strip limiting its lateral movement and adapted to prevent ingress of material into the space behind it.

8. In a material delivery means, a chute and a chute closing member adapted to be moved to prevent discharge through the chute, and sealing means interposed between the chute and the chute closing member including a sealing element fixed upon one of said members, and an opposed yielding sealing element mounted upon the other member 10 and formed for sealing contact with the first member.

9. In a material delivery means, a chute and a chute closing member adapted to be moved to prevent discharge through the chute, and sealing means interposed between the chute and the chute closing member including yieldingly opposed sealing elements 20 upon the chute and the chute closing member.

25 10. In a material delivery means, a chute and a chute closing member adapted to be moved to prevent discharge through the chute, and sealing means interposed between the chute and the chute closing member including yieldingly opposed sealing segments 30 upon the chute and the chute closing member.

35 11. In a material delivery means, a chute and a chute closing member adapted to be moved to prevent discharge through the chute, and sealing means interposed between the chute and the chute closing member, including opposed sealing elements mounted 40 upon the chute and chute closing member, and yielding means for thrusting one against the other.

45 12. In a material delivery means, a chute and a chute closing member adapted to be moved to prevent discharge through the chute, and sealing means interposed between the chute and the chute closing member, including a sealing element fixed upon the chute, and an opposed yielding sealing element 50 mounted upon the chute closing member.

55 13. In a skip hoist, a chute adapted to fill a skip, a chute closing member adapted to be moved to permit discharge through said chute, in combination with a guide member adapted to move with said closing member and to guide the discharge of material from said chute, and sealing means interposed between the chute and the chute closing member, including yieldingly opposed sealing segments 60 mounted upon the chute and the chute closing member.

65 14. The combination with a fixed chute having side walls and a pivoted combined gate and chute associated therewith having

side walls, of sealing means interposed between said side walls to prevent escape of material into the space between them, said sealing means including a flexible arcuate member generally concentric with the axis of rotation of the pivoted chute. 70

15. The combination with a fixed chute having side walls and a pivoted combined gate and chute associated therewith having side walls, of sealing means interposed between said side walls to prevent escape of material into the space between them, said sealing means comprising engaging arcuate members, one of them flexible, both concentric with the axis of rotation of the chute. 75

16. The combination with a fixed wall member and a pivotally movable wall member parallel therewith, of sealing means interposed between them, comprising an arcuate, yielding sealing strip on one, adapted to engage and slide upon the other. 80

Signed at Philadelphia, county of Philadelphia and State of Pennsylvania, this 21st day of March, 1929.
